UNITED STATES PATENT OFFICE.

ALPHONSO S. CAMPBELL, OF WEST MEDFORD, MASSACHUSETTS, ASSIGNOR TO A. S. CAMPBELL COMPANY, OF BOSTON, MASSACHUSETTS, A CORPORATION OF MASSACHUSETTS.

CURTAIN-WINDOW INSTALLATION.

Application filed August 21, 1920. Serial No. 405,091.

To all whom it may concern:

Be it known that I, ALPHONSO S. CAMPBELL, a citizen of the United States, and resident of West Medford, in the county of Middlesex, State of Massachusetts, have invented an Improvement in Curtain-Window Installations, of which the following description, in connection with the accompanying drawings, is a specification, like characters on the drawings representing like parts.

Part 15 This invention relates to improvements in curtain window installations, and more particularly, though not exclusively, to improvements in the suspension of curtain window installations. It is among the objects of the invention to provide a simple, inexpensive and effective suspension for curtain windows and to improve the appearance of curtain window installations.

In the drawings, which show a preferred form of one embodiment of my invention:—

Figure 1 is an elevation showing a preferred curtain window installation;

25. Fig. 2 is a section on the line 2—2 of Fig. 1;

Fig. 3 is an enlarged view showing a detail of a preferred form of terminal for the curtain window suspension means;

30 Fig. 4 is a section on the line 4-4 of Fig. 3; and

Fig. 5 shows a modification more fully described hereinafter.

Referring to the drawings and to the preferred form of my invention selected for illustrative purposes, I have shown a curtain window including a glass 6 and suspension means herein typified by webbings 7. The glass 6 is held in the curtain 8 by a frame, which preferably is formed of sheet metal parts which may generally resemble those shown in my copending application Serial No. 218,673, filed February 23, 1918. The preferred form of frame illustrated in-

45 cludes three principal parts, the frame ele-
ment 9, the clamping element 10 and the
covering element 11. The clamping element
10 may be provided with a peripheral pro-
jection or bead 12, over which the covering
50 element 11 may snap. In the preferred form
of my invention shown in Fig. 3, the bead
12 is cut away to admit of passage there-
through of the webbing 7 constituting a pre-
ferred form of suspension means and the

suspension means terminal portion 13 adapted to underlie the bear 12 at opposite sides of the opening therethrough. The terminal portion 13 may also be provided with prong projections 14 adapted to be forced into the webbing, and the securing means, herein typified by the screw 15 for securing the glass to the curtain by holding the frame portions in assembled relationship, may pass through the terminal 13, thereby insuring its proper positioning and insuring the firm clamping of the suspension means or webbing 7. 55 60 65 70

In Fig. 5 I have shown a somewhat different construction wherein the curtain fabric 8 is provided with a lining 20, the webbing 7 lying between the curtain fabric and the lining and the webbing 7 being held in assembled relationship to the curtain window frame by prongs 21 projecting from the frame part into the webbing and being pressed thereagainst by the securing means typified by the screw 15.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims.

1. A curtain window installation comprising, in combination, a glass, the curtain fabric, a frame member and curtain window suspension means for relieving the fabric of the weight of the window, said frame comprising two units, one on each side of the fabric, one of said parts having an outwardly projecting flanged-over rim, and said suspension means having a terminal portion engaging beneath said rim on each side. 90 95

2. A curtain window installation comprising, in combination, a glass, the curtain fabric, a frame member and curtain window suspension means for relieving the fabric of the weight of the window, said frame comprising two units, one on each side of the fabric, one of said parts having a flanged-over rim, said suspension means having a terminal portion engaging beneath said rim, and a covering part engaging over

- said rim to conceal and protect said unit having said flanged-over rim, and to retain said terminal portion in assembled relation to said unit.
5. A curtain window installation comprising, in combination, a glass, the curtain fabric, a frame, and curtain window suspension means for relieving the fabric of the weight of the window, said frame providing a flange having a space therethrough and said suspension means having a terminal portion engaging beneath said flange adjacent said space, said terminal portion having projections engaging the fabric of the suspension webbing, and a screw pressing said terminal portion and webbing toward the curtain fabric.
5. The combination with a fabric wall, and a window adapted to be held in said wall, of suspension means for the window including a strip independent of the fabric wall and terminating at its lower end in a metallic piece extending beyond the edges of the strip, and window frame means comprising two opposed units with securing means adapted to clamp the units together with the fabric wall and the metallic piece held between them, one of said units having a flange at its upper edge and a gap in said flange, the lower end of the strip passing through said gap and the extremities of the metallic piece extending under the flange, whereby substantially the whole weight of the window is carried by the strip independently of the securing means which clamps the units together.
4. A curtain window installation comprising, in combination, a glass, the curtain fabric, a frame, and curtain window suspension means for relieving the fabric of the weight of the window, said frame providing a flange having a space therethrough and said suspension means having a terminal portion engaging beneath said flange adjacent said space, said terminal portion having projections engaging the fabric of the suspension

In testimony whereof, I have signed my name to this specification.

ALPHONSO S. CAMPBELL.
